Attorneys.

Patented July 17, 1928.

UNITED STATES PATENT OFFICE.

MOSES E. ST. AMOUR, OF FAUST, NEW YORK.

OVERALLS.

Application filed March 10, 1926. Serial No. 93,679.

This invention relates to union garments and aims to provide novel means for permitting free movement of the body of the wearer eliminating any possibility of the body portion becoming disconnected or torn from the lower portion when the person clothed in the garment bends forwardly.

Another object of the invention is to provide a guard for the elastic member disposed between the body portion and nether garment of the device so that the elastic member will be securely held in position against tearing and the elastic member will be invisible at all times.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a rear elevational view of a union garment constructed in accordance with the invention, a portion of the guard band being broken away to illustrate the elastic member.

Figure 2 is a sectional view taken on line 2-2 of Figure 1.

Referring to the drawing in detail, the reference character 5 designates the body portion of the garment and the reference character 6 indicates the nether portion of the garment.

As illustrated by Figure 2 of the drawing, the lower rear edge of the body portion 5 is folded upwardly as at 7 while the upper rear edge of the nether portion 6 is folded downwardly as at 8.

The guard flap embodies a length of cloth material folded intermediate its side edges to provide outer section 9 and inner section 10, between which sections the elastic strip 11 is secured, the upper edge of the elastic

member being shown as folded downwardly between the upper edges of the sections 9 and 10, securely locking the elastic strip 11 in position.

Lines of stitching indicated at 12 pass through the body portion 5, and sections 9 and 10 of the guard flap to secure the elastic member 11 in position. This guard flap 55 is also secured along its ends to the body portion of the garment.

A line of stitching indicated at 13 secures the lower edge of the elastic strip 11 to the nether section 6 so that movement of the body portion will be permitted independently of the nether section.

From the foregoing it will be obvious that a person wearing the garment may bend freely, the elastic member compensating for the movement of the body relieving the body portion and nether section of the garment of undue strain.

It will be further seen that due to the construction of the guard flap, the elastic strip 70 will be securely held in position and at the same time will be invisible.

I claim:

In a union garment, a body section and a nether section separated at the back thereof, a guard flap for covering the space between the body section and nether section, said guard flap embodying a length of cloth material folded upon itself defining outer and inner layers, a strip of elastic material 75 having one edge folded outwardly and secured between the layers, said strip of flexible material and guard flap being secured to the body section, said strip of flexible material being secured along its lower edge 80 to the nether section, and said guard flap having its lower edge disposed an appreciable distance below the upper edge of the nether garment to which the lower edge of the elastic strip is secured to cover the strip 85 of flexible material.

In testimony that I claim the foregoing as my own, I have hereto affixed my signature.

MOSES E. ST. AMOUR.
